UNITED STATES PATENT OFFICE.

FRANK PELIKAN, OF SAN FRANCISCO, CALIFORNIA.

TELLER'S CAGE.

Application filed June 8, 1925. Serial No. 35,833.

To all whom it may concern:

Be it known that I, FRANK PELIKAN, a citizen of the United States, residing in the city and county of San Francisco and State of California, have invented a new and useful Improvement in a Teller's Cage, of which the following is a specification.

My invention relates to improvements in tellers' cages for banks and the like wherein a movable shutter for a customer's window is operated in conjunction with a booth and door arranged outside of said window to permit access to the window to only one person at a time and to prevent the escape of a person from the window in event of attempted robbery.

The primary object of my invention is to provide an improved teller's cage for banks and the like which will afford protection against robbery and prevent the escape of persons attempting to rob or defraud the bank.

Another object is to provide an improved cage which will afford privacy to customers in transacting business with the bank.

A further object is to provide an improved teller's cage of the character described wherein a shutter normally closing a customer's window of said cage can be opened only when the door to a booth arranged outside of said window is locked whereby the teller is protected from attack by persons other than a single individual within the booth.

Another object is to provide a device of the character described wherein persons transacting business with a teller are locked within a booth outside the window while the customer's window is open to prevent the escape of a person attempting to rob or defraud the bank.

A further object is to provide a device of the character described having improved means for opening and closing a shutter for a customer's window.

Another object is to provide an improved device of the character described wherein an electric circuit supplying power to the actuating means for moving a shutter relative to a customer's window is arranged to be automatically broken when the shutter reaches either extreme position and to be controlled by a single control switch for moving the shutter in either direction.

A still further object is to provide a de-

vice of the character described which is simple in construction and operation, which will be positive in its action and which will afford privacy and safety without inconveniencing either the teller or the customers of the bank.

I accomplish these and other objects by means of the device disclosed in the drawings forming a part of the present specification wherein like characters of reference are used to designate similar parts throughout said specification and drawings and in which,

Fig. 1 is a broken horizontal section of a portion of a teller's cage disclosing the shutter actuating mechanism and the door locking means.

Fig. 2 is a similar view showing a modified form of door for the customer's booth outside the teller's cage.

Fig. 3 is a broken vertical section taken upon the line 3—3 of Fig. 1 in the direction indicated, parts being broken away to disclose the actuating mechanism.

Fig. 4 is a broken front elevation, partly in section disclosing the manner in which the doors are locked and released.

Fig. 5 is a front elevation of the shutter and actuating means therefor and including a conventional wiring diagram of the electrical connections.

Fig. 6 is a plan view of the floor plate by which a revolving door is normally moved by gravity to a fully closed position.

Fig. 7 is a side elevation of the plate showing the relation of the door and rollers relative thereto.

Fig. 8 is a broken sectional detail showing the manner in which the door may be released manually.

Referring to the drawings the numeral 1 is used to designate in general the counter of a teller's cage having partitions 2 separating said cage from adjacent cages and having one or more customer's windows 3 through which business is transacted between the teller and customers of the bank. A booth 4 is provided outside of each window 3. Doors 6 are mounted in connection with the booth to open and close entrances 7 provided therein. Each cage is preferably provided with two windows 3 positioned adjacent the center of the cage and the booths arranged outside of said windows are separated by a partition 8 arranged between the

windows, but this particular arrangement may of course be modified in various ways to meet the requirements of any particular installation.

5 A shutter 9 is mounted in connection with each window 3 for opening and closing the same, said shutters being provided with mounting elements 11 threaded onto threaded shafts 12 mounted within the upper portion 10 of partitions 13 across the front of the cage. Suitable electric motors 14 are mounted adjacent the ends of the shafts 12 and connected to said shafts for imparting rotation thereto whereby the elements 11 15 may be moved longitudinally along the shafts to move the shutters to open or closing relation to the windows 3.

Each motor 14 is connected to a suitable 20 source of power 15 through a reversing control switch 16 mounted in any suitable location conveniently accessible to a teller within the cage but inaccessible to a person in a booth 4. Current is directed by the reversing switch 16 through independent opening 25 and closing circuits as shown in Fig. 5 of the drawings whereby the current from the source of power is directed in opposite directions through the motor to cause a rotation of said motor in a direction adapted to 30 obtain the desired movement of the shutter 9 associated therewith.

The opening circuit consists of a connection 17 extending from one terminal 18 of the switch 16 through a pair of contacts 19 35 arranged to be bridged by a contact plate 21, to complete a circuit therebetween. From the contacts 19 the current is conducted through a connection 22, switch 23, and connection 24 to a connection 26 connected to the motor 14 and thence through a connection 27 to a return contact 28 of the switch 16.

The closing circuit consists of a connection 29 extending from a terminal 34 of the switch 16 to the connection 27 whereby current is directed in opposite direction to and 45 through the motor 14. From the motor the current is conducted through the connection 26 and a switch 32 and connection 33 to a return contact 31 of the switch.

The switches 23 and 32, which may be of any suitable construction adapted to normally close the circuit therethrough, are mounted in positions adjacent the extreme 55 positions of opposite edges of the shutter 9 and are arranged to be actuated by the movement of the shutter into engagement therewith to break the circuit by virtue of which the shutter is at the moment being actuated.

60 The contacts 19 are resiliently mounted within a partition of the booth adjacent the free edge of the adjacent door 6, preferably at widely spaced points, said contacts preferably being in the form of buttons extending outwardly slightly through the facing of

the partition in position to be engaged by the contact strip 21 which is set into the edge of the door in such manner as to engage both contacts and complete a circuit therebetween only when the door is in fully closed position, the purpose of this arrangement being hereinafter more fully explained.

70 The doors 6 may be made either of the swinging type as shown in Fig. 1 of the drawings or of the revolving type as shown 75 in Fig. 2. In either case the doors are arranged to be moved by gravity to a normally fully closed position. This is accomplished in the case of a swinging door by mounting the door upon the well known 80 self-closing hinges 35 whereby the weight of the door acting upon inclined edges of the hinge butts operates to swing the door closed when said door is swung outwardly from the closed position. In the case of a revolving door I provide a floor plate 36 having a central recess 37 forming a mounting for the lower end of an axis about which the door is revolved. The plate 36 is provided with a flanged edge 38 adapted to form a 90 track for rollers 39 mounted upon the bottom of the door, said flange having an undulating upper surface forming low points 41 defining closed positions for the doors. The flange is provided with convex arcuate 95 track portions 42 between the low points whereby the weight of the door supported upon the convex surface by the rollers will cause the door to move to the nearest closed position as defined by low points in the 100 flange, the rollers resting in said low points until the door is partially revolved to admit a person to the booth. In this form of door, four door portions are preferably arranged about a common axis, said door portions 105 being arranged at right angles to each other and the axis so positioned that two of the door portions will act as partitions for the booth at all times as shown in Fig. 2 of the drawings. A contact strip 21 is 110 mounted within the outer edge of each door portion so that a connection will be made between the contacts 19 when any door portion is moved adjacent thereto.

115 Bars 43 are pivotally mounted within suitable bearings 44 positioned within the upper portion of the partition 8. Each bar 43 is provided with an extension 46 at one end adapted to be moved into engagement with a notch 47 formed in the upper edge 120 of the adjacent door whereby said door may be locked in closed position. An extension 48 is formed upon the opposite end of the bar and is arranged to be engaged by the adjacent shutter mounting element 11, or other suitable element moving with the shutter when said element is moved to the closed position, for moving the bar pivotally within the bearings 44 and thereby causing the extension 46 to be moved out of engagement 125 130

with the notch 47 to release the door. The bar and extension are so mounted that the weight of the extensions will normally cause the extension 46 to be moved downwardly by gravity into engagement with the door and to maintain locking engagement therewith until released by movement of the shutter against the extension 48 when the shutter is closed.

10 In operation my invention is as follows: The shutter 9 of any particular window is normally kept closed to protect the teller from observation and possible attack by robbers. While in the closed position the shutter holds the bar 43 in door releasing position so that the door 6 of the booth 4 adjacent such window may be opened to admit a customer into the booth. When a customer enters the booth to transact business with the teller, the teller moves the switch 16 to engage the contacts 18 and 28, thereby directing current through the shutter opening circuit as indicated by the arrows in Fig. 5 of the drawings to operate 20 the motor 14 in a direction adapted to move the shutter along the rotating shaft 12 to an open position as indicated in dotted lines in said Fig. 5. Before it is possible for the circuit to be completed to the motor 14 it is necessary that the door 6 of the booth be 30 in fully closed position whereby the contact strip 21 will be caused to bridge the contacts 19.

As the shutter 9 is moved the extension 48 of the bar 43 will be released and the weight of said extension and the extension 46 will cause the extension 46 to drop into the notch 47 of the door thereby locking said door in closed position so long as the shutter remains open. The customer is now locked within the booth and may transact his business in private with the teller through the opened window 3 of the cage. When the business has been completed the teller moves 45 the control switch 16 to engage the contacts 31 and 34 thereby closing the circuit to the motor 14 and directing current through said motor in a direction opposite to that resulting in the opening of the shutter. The motor is now rotated and the shutter 9 moved along the shaft 12 to closed position. As the shutter approaches the closed position, the extension 48 of the bar 43 is engaged and the bar moved to cause the extension 46 to release the door and thereby permit the customer to leave the booth.

The switches 23 and 32 placed in the opening and closing circuits respectively are operated as above explained by the movement of the shutter to either extreme position to break the then actuating circuit. Thus when the window is being opened the actuating circuit will be closed until the instant the shutter reaches the extreme position and operates the switch 23 to break the

circuit and prevent further movement of the shutter. The opening circuit is now broken at the switch 23 and the closing circuit broken at the switch 16 so that both circuits remain inactive so long as the shutter remains in open position. When now the switch 16 is operated to close the shutter closing circuit, the movement of the shutter away from the switch 23 will release said switch to circuit closing position. The current through the circuit containing the switch 23 will however be now broken at the switch 16 so that no current will be directed through the opening circuit connections. The switch 32 operates in identical manner to break the actuating circuit when the shutter reaches the extreme position and to restore a closed connection through said switch as soon as the circuit therethrough is broken at the switch 16. In this manner the switches 23 and 32 are made to operate in conjunction with the control switch 16 whereby a single operation of the switch 16 will serve to open or close the window as the case may be.

The slot 47 formed in the door 6 to receive the locking bar extension 46 is made sufficiently wide to insure the entrance of the extension into said notch when the window is opened, the width of the strip 21 being proportioned to the width of the notch 47 in such a way that the notch 47 must necessarily be in position to receive the extension 46 before contact is made between the strip 21 and the contacts 19. The provision is made to insure the locking of the booth door 6 before the window can be opened.

From the above explanation it will be noted that the window 3 is closed at all times when the door 6 is unlocked, and that the door 6 is locked at all times when the window 3 is open. This arrangement protects the teller from observation of persons other than the individual within the booth and an attack by a number of persons in attempt to commit robbery is made impossible. At the same time, the person within the booth is locked in such a manner that any person attempting to rob or defraud the bank can be kept imprisoned within the booth while officers are summoned to effect his arrest. The arrangement thus forms a means for providing protection to the teller and guarding against the escape of persons attempting any felonious act. In addition to the protection afforded, the arrangement affords privacy to the transactions between the teller and the customers of the bank.

The windows 3 and booths 4 are preferably arranged in pairs as shown in the drawings so that one window may be opened while the other window is being closed. Customers will thus be admitted into the booths alternately and in this manner quicken the conduct of the bank's business without detracting from the protection afforded and the

privacy afforded each customer. The number and arrangement of the windows and booths however must necessarily be adapted to the requirements of any particular bank.

- 5 In order to prevent a customer from being inadvertently locked in the booth due to the failure of the source of electrical power, I provide a recess 51 in the end of each bar 43 to be engaged by a square key adapted 10 to be inserted into engagement with said recess through a small aperture 53 formed in the adjacent panel of the cage. The key may be kept in any place out of reach of a person within the booth and will only be 15 used upon rare occasions when no power is available for closing the window and releasing the door.

From the above explanation it will be seen that I have provided a new and improved 20 cage for tellers and the like which will afford privacy and protection for the teller. The specific construction and arrangement of the parts shown in the drawings may of course be modified in many ways without departing 25 from the spirit of the invention. I therefore do not wish to restrict myself to the precise construction shown but desire to avail myself of all modifications which may fall within the scope of the appended claims.

30 Having thus described my invention what I claim as new and desire to secure by Letters Patent is—

1. The combination with a teller's cage having a customer's window therein, of a 35 booth arranged outside of said window and having an entrance; a door arranged to open and close said entrance; a shutter movable to open and close the customer's window; means for locking the door in closed position 40 when the shutter is opened; and means for preventing the opening of the shutter when the door is open.

2. The combination with a teller's cage having a customer's window therein, of a 45 booth arranged outside of said window and having an entrance; a door arranged to open and close said entrance; a shutter movable to open and close the customer's window; means for preventing the opening of the 50 shutter when the door is in open position; and means actuated by the opening of the shutter for locking the door in closed position while said shutter is opened.

3. The combination with a teller's cage 55 having a customer's window therein, of a booth arranged outside of said window and having an entrance; a door arranged to open and close said entrance; a shutter mounted adjacent the customer's window; electrically operated means for moving the 60 shutter to open and close said window; means for breaking the electrical operating circuit to prevent the shutter from being moved to open position when the door is open; and means actuated by the opening 65

of the shutter for locking the door in closed position when the shutter is open.

4. The combination with a teller's cage having a customer's window therein, of a 70 booth arranged outside of said window and having an entrance; a door arranged to open and close said entrance; means actuated by gravity for normally moving the door to a closed position; a shutter mounted in connection with the customer's window; 75 electrically actuated means for moving the shutter to open and closed positions; means for preventing the opening of the shutter when the door is not in fully closed position; and means for locking said door in closed 80 position when the shutter is open.

5. The combination with a teller's cage having a customer's window therein, of a 85 booth arranged outside of said window and having an entrance; a door arranged to open and close said entrance; means actuated by gravity for normally moving the door to a closed position; a shutter mounted in connection with the customer's window; 90 electrically actuated means for moving the shutter to open and closed positions; means mounted in connection with the door for breaking the electrical operating circuit to prevent the shutter from being moved to open position when the door is open; and means actuated by the opening of the shutter 95 for locking the door in closed position when the shutter is open.

6. The combination with a teller's cage having a customer's window therein, of a 100 booth arranged outside of said window and having an entrance; a door arranged to open and close said entrance; a shutter mounted in connection with the customer's window; a motor mounted adjacent the 105 shutter and electrically connected with a source of power; means connected between the motor and the shutter for moving said shutter to open and closed positions; means mounted in connection with the door for breaking the electrical connection through the motor to prevent movement of the shutter to open position when the door is not in fully closed position; and means for locking the door in closed position when 110 the shutter is open.

7. The combination with a teller's cage having a customer's window therein, of a 115 booth arranged outside of said window and having an entrance; a door arranged to open and close said entrance; a shutter mounted in connection with the customer's window; a motor mounted adjacent the 120 shutter; means connected between the motor and the shutter for moving the shutter relatively to the window; separate electric 125 circuits connecting the motor to a source of power for moving said shutter to open and closed positions; means mounted in connection with the door and with the shutter 130

- opening circuit to break said circuit and prevent the operation of the motor to open the shutter when the door is not in fully closed position; and means for locking the door in closed position when the shutter is open.
8. The combination with a teller's cage having a customer's window therein, of a booth arranged outside of said window and having an entrance; a door arranged to open and close said entrance; a shutter mounted in connection with the customer's window; a motor mounted adjacent the shutter; means connected between the motor and the shutter for moving said shutter to open and closed position; separate electric circuits connecting the motor to a source of power for actuating the motor to move the shutter to open and closed positions; contacts mounted adjacent the sides of the window for breaking the actuating circuit when the shutter is moved to either extreme position; and contacts mounted in connection with the door and shutter opening circuit for breaking said circuit when said door is not in fully closed position whereby the shutter may be opened only when the door is closed.
9. The combination with a teller's cage having a customer's window therein, of a booth arranged outside of said window and having an entrance; a door arranged to open and close said entrance; a shutter mounted in connection with the customer's window; a motor mounted adjacent the shutter; means connected between the motor and the shutter for moving said shutter to open and closed position; separate electric circuits connecting the motor to a source of power for actuating the motor to move the shutter to open and closed positions; contacts mounted adjacent the sides of the window for breaking the actuating circuit when the shutter is moved to either extreme position; and contacts mounted in connection with the door and the shutter opening circuit for breaking said circuit when said door is not in fully closed position whereby the shutter may be opened only when the door is closed; and means for locking the door in closed position when the shutter is opened.
10. The combination with a teller's cage having a customer's window therein, of a booth arranged outside of said window and having an entrance; a door arranged to open and close said entrance; a shutter mounted in connection with the customer's window; a motor mounted adjacent the shutter; means connected between the motor and the shutter for moving said shutter to open and closed positions; separate electric circuits connecting the motor to a source of power for actuating the motor to move the shutter to open and closed positions; contacts mounted adjacent the sides of the window for breaking the actuating circuit when the shutter is moved to either extreme position; and contacts mounted in connection with the door and the shutter opening circuit for breaking said circuit when said door is not in fully closed position whereby the shutter may be opened only when the door is closed; and means for locking the door in closed position when the shutter is opened.
11. The combination with a teller's cage having a customer's window therein, of a booth arranged outside of said window and having an entrance; a door arranged to open and close said entrance; a shutter mounted in connection with the customer's window; a motor mounted adjacent the shutter; means connected between the motor and the shutter for moving said shutter to open and close the window; electrical connections connected between the motor and a source of power; and a reversing switch mounted in association with said connections for controlling the opening and closing circuits through the motor, said switch being movable into engagement with connections adapted to conduct current through the motor in either direction to obtain rotation in a desired direction whereby the shutter may be moved to open or close the window; and contacts mounted in connection with the door and with the connections of the shutter opening circuit for breaking said circuit when the door is not in a fully closed position to prevent the shutter from being opened when the door is not closed.
12. The combination with a teller's cage having a customer's window therein, of a booth arranged outside of said window and having an entrance; a door arranged to open and close said entrance; a shutter mounted in connection with the customer's window; a motor mounted adjacent the shutter; means connected between the motor and the shutter for moving said shutter to open and close the window; electrical connections connected between the motor and a source of power; and a reversing switch mounted in association with said connections for controlling the opening and closing circuits through the motor, said switch being movable into engagement with connections adapted to conduct current through the motor in either direction to obtain rotation in a desired direction whereby the shutter may be moved to open or close the window; and contacts mounted in connection with the door and with the connections of the shutter opening circuit for breaking said circuit when the door is not in a fully closed position to prevent the shutter from

being opened when the door is not closed; and means for locking the door in closed position when the window is opened.

13. The combination with a teller's cage having a customer's window therein, of a booth arranged outside of said window and having an entrance; a door arranged to open and close said entrance; a shutter mounted in connection with the customer's window; 10 a motor mounted adjacent the shutter; a threaded shaft connected between the motor and the shutter for moving said shutter relative to the window; means for forming an electric circuit through the motor for moving the shutter to open or closed position; and means for breaking the shutter opening circuit when the door is not in a fully closed position.

14. The combination with a teller's cage having a customer's window therein, of a booth arranged outside of said window and having an entrance; a door arranged to open and close said entrance; a shutter mounted in connection with the customer's window; 25 a motor mounted adjacent the shutter; a threaded shaft connected between the motor and the shutter for moving said shutter relative to the window; means for forming an electric circuit through the motor for moving the shutter to open or closed position; and means for breaking the shutter opening circuit when the door is not in fully closed position; and means for locking the door in closed position when the window is opened.

15. The combination with a teller's cage having a customer's window therein, of a booth arranged outside of said window and having an entrance; a door arranged to open and close said entrance; shutter mounted in connection with the customer's window; means for moving said shutter to open or closed relation to the window; and gravity actuated means for locking the door when the shutter is opened, said means being moved and held in door releasing position when the shutter is moved to close the window.

16. The combination with a teller's cage having a customer's window therein, of a booth arranged outside of said window and having an entrance; a door arranged to open and close said entrance; a shutter mounted in connection with the customer's window; 50 means for moving said shutter to open or closed relation to the window; and a bar pivotally mounted within a wall of the booth and provided with an extension adapted to be moved into locking engagement with the door to prevent said door from being opened when the shutter is in open position.

17. The combination with a teller's cage having a customer's window therein, of a 60 booth arranged outside of said window and

having an entrance; a door arranged to open and close said entrance; a shutter mounted in connection with the customer's window; means for moving said shutter to open or closed relation to the window; and a bar pivotally mounted within a wall of the booth and provided with an extension adapted to be moved into locking engagement with the door to prevent said door from being opened when the shutter is in open position; and means for preventing the opening of the shutter when the door is not in fully closed position.

18. The combination with a teller's cage having a customer's window therein, of a 80 booth arranged outside said window and having an entrance; a door arranged to open and close said entrance; a shutter mounted in connection with the customer's window; means for moving the shutter to open or 85 closed relation to the window; and a bar pivotally mounted within a wall of the booth and provided with extensions at each end thereof adapted to engage the door and the shutter whereby the door is locked in 90 closed position when the window is opened and the door released when the window is closed.

19. The combination with a teller's cage having a customer's window therein, of a 95 booth arranged outside said window and having an entrance; a door pivotally mounted in connection with said entrance and adapted to be moved by gravity to a 100 fully closed position relative thereto; a shutter mounted in connection with the customer's window; means for moving said shutter to open and close said window; a bar pivotally mounted within one wall of the booth; an extension formed upon one end of said bar adapted to be moved by gravity 105 to engage and lock the door in closed position when the window is open; and an extension formed upon the other end of the bar and adapted to be engaged by the shutter to move said bar to door releasing position 110 when the window is closed.

20. The combination with a teller's cage having a customer's window therein, of a 115 booth arranged outside said window and having an entrance; a door pivotally mounted in connection with said entrance and adapted to be moved by gravity to a fully closed position relative thereto; a shutter mounted in connection with the customer's window; means for moving said shutter to open and close said window; a bar pivotally mounted within one wall of the booth; an extension formed upon one end of said bar and adapted to be moved by gravity 120 to engage and lock the door in closed position when the window is open; and an extension formed upon the other end of the bar and adapted to be engaged by the shutter to move said bar to door releasing position 125 130

tion when the window is closed; and means for preventing the opening of the window when the door is not in fully closed position.

21. The combination with a teller's cage 5 having a customer's window therein, of a booth arranged outside said window and having an entrance; a door pivotally mounted in connection with said entrance and adapted to be moved by gravity to a 10 fully closed position relative thereto; a shutter mounted in connection with the customer's window; means for moving said shutter to open and close said window; a bar pivotally mounted within one wall of the

booth; an extension formed upon one end of 15 said bar and adapted to be moved by gravity to engage and lock the door in closed position when the window is open; and an extension formed upon the other end of the bar and adapted to be engaged by the shutter to move said bar to door releasing position when the window is closed; and means accessible to the teller only for moving the bar to door releasing position independently 20 of the movement of the shutter. 25

In witness whereof I hereunto set my signature.

FRANK PELIKAN.
